C. D. MARLOWE, SR.
ROCKING TOY VEHICLE.
APPLICATION FILED SEPT. 26, 1921.

1,414,368.

Patented May 2, 1922.

By *Watson E. Coleman*
Attorney

UNITED STATES PATENT OFFICE.

CLINTON D. MARLOWE, SR., OF JOHNSTOWN, PENNSYLVANIA.

ROCKING TOY VEHICLE.

1,414,368.

Specification of Letters Patent. Patented May 2, 1922.

Application filed September 26, 1921. Serial No. 503,273.

To all whom it may concern:

Be it known that I, CLINTON D. MARLOWE, Sr., a citizen of the United States, residing at Johnstown, in the county of Cambria and State of Pennsylvania, have invented certain new and useful Improvements in Rocking Toy Vehicles, of which the following is a specification, reference being had to the accompanying drawings.

10 This invention relates to amusement devices, particularly to toy vehicles, and has for its object the provision of a toy vehicle which is formed as a representation of a horse or other animal and which has a rocking movement in combination with a rolling movement, the construction being such that the device is propelled by imparting movement thereto by the rider.

An important and more specific object is 20 the provision of a toy of this character which includes a wheel supported frame upon which is rockably mounted a support formed as the representation of an animal and upon which the rider sits, the rockable support 25 or element being connected with a crank shaft which carries two of the ground engaging wheels so that as the support is rocked the device will be caused to travel along the ground.

30 Another object is the provision of a device of this character in which the front axle carries foot rests which serve to enable the rider to impart the necessary rocking movement to the device and which also serve as 35 steering means for controlling the direction of travel.

Yet another object is the provision of a 40 toy of this character in which the rockable element has a spring associated therewith which will assist in the propulsion of the device at certain positions of the rockable element.

An additional object is the provision of a 45 device of this character which will be simple and inexpensive in manufacture, easy to operate even by the very young, which will also be highly entertaining and amusing in use, durable in service and a general improvement in the art.

50 With the above and other objects and advantages in view, the invention consists in the details of construction to be herein-after more fully described and claimed, and illustrated in the accompanying drawings, 55 in which:

Figure 1 is a side elevation showing the

rockable member at one limit of its movement;

Figure 2 is a longitudinal sectional view with the rockable member at the other limit 60 of its movement;

Figure 3 is a front elevation; and

Figure 4 is a plan view with the rockable member removed.

Referring more particularly to the drawings, I have shown the device as comprising a supporting frame which includes a pair of bars 10 arranged in V-shaped relation and provided at their converging ends with upper and lower plates 11 which project forwardly and between which is pivoted, as shown at 12, the front axle 13 which has its ends carrying spindles 14 upon which are journaled wheels 15. The rear ends of the bars 10 are reinforced by metal plates or strip 16 and journaled through the rear ends and the strips 16 is a shaft 17 formed centrally with a crank portion 18. Rotatable upon one end of the shaft 17 is a wheel 19 while secured upon the other end is a 80 wheel 20.

Rising from the intermediate portion of the frame defined by the bars 10 is a standard 21 which is formed at its lower end with a reduced extension 22 which is triangular in cross section and which conformingly fits between the bars 10. A bolt 23 passes through the bars 10 and through the extension 22 for the purpose of holding the standard 21 in position and also 90 strengthening the frame. It should also be stated that I provide a bolt 24 which passes transversely through the forward extremities of the bars 10. The upper end of the standard 21 is reduced in thickness to define an upright extension 25 which is forked, 95 as shown at 26.

The numeral 27 designates the rockable member which is shown in the present instance as the representation of a horse though 100 it is to be distinctly understood that it might be the representation of any other animal, bird, or in fact any other object. This rockable member is provided with a saddle 28 of any preferred construction and which may 105 be as elaborate as desired. Projecting through the neck portion of the rockable member and extending beyond the sides thereof are handle bars 29 adapted to be grasped by the rider for preventing falling 110 off. This rockable member is disposed upon the top of the standard 21 and is formed at

its lower edge with a recess 30 which receives the forked extension 25, and communicating with this recess is an upwardly extending bore 31 within which is located a coil spring 32 which has its upper end connected with a bolt 33 which passes transversely through the rockable member. The standard 21 is also formed with a bore 34 which receives the spring 32 and the latter has its lower end 10 connected with the bolt 23.

In order to impart rocking movement to the member 27, I provide a pitman 35 which is connected at one end with the crank 18 of the shaft 17 and which has its other end pivoted upon the bolt 36 which passes transversely through a recess 37 in the lower edge of the rockable member.

Secured upon the front axle 13 are inverted U-shaped brackets 38 which constitute 20 foot rests for the rider so that the rider may obtain the necessary purchase for effecting rocking movement of the member 27. These brackets also serve as steering means for controlling the direction of travel.

25 In the use of the device the operator sits upon the saddle 28 with his feet upon the brackets 38 and with his hands grasping the handle bars 29. The operator then rocks the member 27 back and forth whereupon the 30 member fulcrums upon the front and rear edges of the standard 21 alternately in a manner similar to the action of a platform rocker. As the member 27 rocks back and forth upon the standard it is apparent that 35 the pitman 35 will operate to turn the rear axle so that the device will be propelled along the ground. Steering is of course effected by pressing upon the proper one of the brackets 38 to swing the front axle. The 40 spring 32 has a two-fold function as it serves not only to connect the rockable member with the frame but also serves to assist in the propulsion. The spring is so arranged that when the rider presses back in the saddle the 45 spring resists the action and is placed under tension so that when the rider subsequently leans forward the spring will assist in the rocking.

From the foregoing description and a study 50 of the drawings it will be apparent that I have thus provided a simply constructed and consequently inexpensive toy vehicle which will be highly entertaining and amusing especially to the young as it not only 55 travels over the ground but produces all the sensation of riding upon a galloping pony. Owing to the simplicity it will be seen that there is nothing to get out of order and that the device should consequently have a long 60 life and efficiently perform the functions for which it is intended.

While I have shown and described a preferred embodiment of the invention it will be apparent that I reserve the right to make

such changes in the form, construction and arrangement of parts as will not depart from the spirit of the invention or the scope of the subjoined claims.

Having thus described my invention, I claim:

1. A toy of the character described comprising a main supporting frame including a pair of converging bars, upper and lower plates secured upon and projecting beyond the forward end of said frame, a front axle 75 pivoted between said plates and carrying ground engaging wheels, a rear axle journaled through said frame and formed with a crank portion, a ground engaging wheel revoluble upon one end of the rear axle, a 80 ground engaging wheel fixed upon the other end of the rear axle, a standard rising from the intermediate portion of the frame and formed with a triangular extension conformingly fitting between said bars, a rockable 85 element pivoted upon said standard, and a pitman pivotally connected with the rockable member and said crank portion of the rear axle.

2. A toy of the character described comprising a main supporting frame, a movable front axle carrying wheels, a rear axle carrying wheels and formed with a crank, a standard rising from the intermediate portion of said frame and having a forked extension at 90 its upper end, a rockable body disposed upon said standard and recessed for the reception of said forked extension, a pitman pivotally connected with said body and with said crank, the body and the standard being 95 formed with bores, and a spring located within said bores and having one end secured to the body and the other end secured within the standard.

3. A toy of the character described comprising a main supporting frame including a pair of converging bars, upper and lower plates secured upon and projecting beyond the forward end of said frame, a front axle pivoted between said plates and carrying ground engaging wheels, a rear axle journaled through said frame and formed with a crank portion, a ground engaging wheel revoluble upon one end of the rear axle, a ground engaging wheel fixed upon the other end of said rear axle, a standard rising from the intermediate portion of the frame and formed with a triangular extension conformingly fitting between said bars, a rockable element pivoted upon said standard, a pitman pivotally connected with the rockable member and said crank portion of the rear axle, and inverted U-shaped brackets secured upon the front axle and constituting foot rests and steering means.

In testimony whereof I hereunto affix my signature.

CLINTON D. MARLOWE, SR.
